UNITED STATES PATENT OFFICE.

RICHARD ZIMMERMANN, OF CHICAGO, ILLINOIS.

GARMENT-SUPPORTER.

No. 920,234.

Specification of Letters Patent.

Patented May 4, 1909.

Application filed March 7, 1908. Serial No. 419,626.

To all whom it may concern:

Be it known that I, RICHARD ZIMMERMANN, a citizen of the United States, residing at Chicago, in the county of Cook and State 5 of Illinois, have invented certain new and useful Improvements in Garment-Supporters, of which the following is a full, clear, and exact specification.

This invention relates to garment supporters of the class commonly known as garters, although it is applicable for supporting garments other than hose, as will be seen from this construction.

The primary object of the invention is to 15 provide an improved garment supporter of the class described that is simple and economical in construction and efficient in its operation.

In devices of this character, heretofore it 20 has been the common practice to provide a flexible member adapted to encircle the body or limb of the wearer, and to provide a single pendent flexible member provided with a single fastener.

One of the special objects of this invention 25 is to provide an improved garment supporter having two flexible pendent members, each provided with fasteners whereby the hose or other garment may be more securely held in 30 the desired position.

A further object of the invention is to provide an improved form of clasp or retainer to be used in conjunction with a flexible garment supporter of the class described.

To the attainment of these ends and the accomplishment of other new and useful objects which will be apparent, the invention consists of the features of novelty described in the following specification, pointed out 40 more particularly in the appended claims, and shown in the accompanying drawing.

In the said drawing Figure 1 is a perspective view of the device. Fig. 2 is a view of the device in position for use on the limb of the wearer. Fig. 3 is an enlarged detail view of the preferred form of clasp or retainer through which the ends of the flexible member is passed in forming the loop for encircling the body or limb of the wearer. Fig. 4 45 is a sectional view on line 4-4 of Fig. 3. Fig. 5 is a detail view showing a modified form of clasp or retainer which may be used instead of the preferred form illustrated in Fig. 3.

The device is constructed from a continuous flexible member 10, which is preferably elastic, and of a single piece of material

although not necessarily so. A loop designed to encircle the limb or body of the wearer is formed in the strip 10 by passing the ends thereof through a suitable clasp or retainer, the preferred form of which is designated in the drawings by the reference character 11. The folds of the member 10 pass through this retainer or clasp loosely so that the loop is readily adjustable while in use, 60 and the free ends 10^a and 10^b of the flexible member 10 are allowed to depend from the clasp or retainer 11 and are provided at their extremities with suitable garment fasteners 12. These fasteners may be of the form 70 illustrated in the drawing, or of any desired construction, and since they form no part of the present invention, no further description of the form herein shown is deemed necessary. These depending ends 10^a and 10^b, 75 having the garment fasteners at their extremities, are preferably adjusted in use to diverge as they extend downwardly, as illustrated in Figs. 1 and 2, in order that the garment fasteners on their extremities may be 80 inserted on the garment to be held at some distance apart from each other, thereby securing the garment very firmly in the desired position and furnishing a much more secure means of fastening the same than that on 85 the ordinary form of device of this character, in which only a single fastener is employed. Since the folds of the flexible member pass somewhat loosely through the apertures 11^a and 11^b in the clasp or retainer, it will be seen 90 that any tensions or strains coming upon the depending ends which support the garment are immediately communicated to the portion encircling the limb or body of the wearer, and tend to tighten the loop, thereby 95 insuring that the loop will be retained in its desired position and so furnish a secure support for the garment.

While the form of clasp or retainer 11 shown in detail in Fig. 3 is the preferred form 100 and consists, as will be seen, of the two ring members spaced a sufficient distance apart to allow the flexible member to pass between them and is joined together at 11^c, yet it will be apparent that many modifications 105 of this member may be provided to take the place of this part without detracting from the purpose or spirit of the invention. For example, a simple form of such modified clasp or retainer is shown in Fig. 5, consisting of a single ring 13 of any suitable material. This form in operation performs the 110

same functions as the preferred form shown in Fig. 3, but it will be seen that it is provided with no means for retaining it on the flexible member when the device is not in use, which permits of its being readily disengaged or lost off the device, which under certain conditions may be objectionable.

What I claim is:

1. A garment supporter comprising a continuous flexible member, a retainer through which the ends of the flexible member are loosely passed to form an adjustable loop beyond the retainer, and means on the free ends of the flexible member for securing them to the garment.
2. A garment supporter comprising a continuous flexible elastic member, a retainer through which the ends of the flexible elastic member are loosely passed to form an adjustable loop beyond the retainer, and means on the free ends of the flexible member for securing them to the garment.
3. A garment supporter comprising a continuous flexible member, suitable garment fasteners on the ends of the flexible member,

and a ring through which a fold of the flexible member is passed to provide a loop beyond the retainer and adapted to encircle the body or limb of the wearer.

4. In a garment supporter in combination, a flexible member provided at each free end thereof with suitable garment fasteners, and a retainer through which a fold of the said flexible member is passed whereby an adjustable loop is formed in said flexible member, said retainer comprising two spaced annular members and suitable means for connecting said annular members together on approximately diametrically opposite portions thereof whereby spaces between said annular members are formed to retain the folds of the flexible member.

In testimony whereof I have signed my name to this specification, in the presence of two subscribing witnesses, on this 3rd day of March A. D. 1908.

RICHARD ZIMMERMANN.
